UNITED STATES PATENT OFFICE.

JOSIAH BRADLEY, OF NEW YORK, N. Y., ASSIGNOR TO ALBERT WESTLAKE, OF NEW YORK, N. Y.

BOTTLE CAPPING AND SEALING MACHINE.

1,160,369.

Specification of Letters Patent.

Patented Nov. 16, 1915.

Application filed April 25, 1913. Serial No. 763,520.

To all whom it may concern:

Be it known that I, JOSIAH BRADLEY, a citizen of the United States, and a resident of Brooklyn borough, New York city, and 5 State of New York, have invented certain new and useful Improvements in Bottle Capping and Sealing Machines, of which the following is a specification.

My invention relates to that class of bottle 10 capping and sealing machines in which the closure is effected by the shaping of the cap around the mouth of the bottle by means of a plunger which serves as a shaping and compression or embossing die. In other 15 words to that class of machinery in which a thin disk of metal, fiber, paper or other desired material is placed between the top of a bottle and a plunger above it, and is then seized and held in position on the top of the 20 bottle and tucked and pressed into the desired shape and position around the end of the bottle neck.

The capping and sealing of milk bottles with a fibrous disk presents peculiar difficulties which are not met with in the ordinary capping and sealing of bottles containing wines, liquors, beer or carbonated or charged liquids in general. A perfect seal 25 or closure for milk bottles does not have to resist any special internal pressure, but it does have to stand considerable rough handling in transit; being frequently used as the means for lifting and holding the bottle on the part of the delivery man. Such a 30 closure must be air-tight, dust-proof, hygienic and sanitary, in the sense that it must not affect the contents of the bottle injuriously, and at the same time this closure must be easily removable.

To attain the desired result it is not sufficient 35 that the fiber disk should be simply bent around, tucked under and pressed into close contact with the outside of the bottle neck ring as is sufficient with ordinary metallic closures for beer and other charged liquids; nor is it sufficient that the inner 40 surface of the closure should be closely pressed at every point into intimate contact with the glass of the bottle. Such simple 45 closures are apt to work loose when made out of the fiber ordinarily employed for caps for milk bottles as there is no adhesive affinity between the glass and the fiber, and the natural springiness of the fiber tends to 50 make it resume its shape by bending away

from the glass enough to break contact somewhere. I have found that the best kind of fiber cap for milk bottles is one composed of a specially prepared fiber suitably applied but capable of easy displacement by giving it the twisting movement which 60 would be necessary if the cap were a screw-cap.

To produce such a closure for milk bottles, I have devised the capping and sealing mechanism shown in the accompanying 65 drawings in which:-

Figure 1, is a vertical section of the plunger head with the plunger and its accessories. Fig. 2, is a bottom plan of the 70 plunger head on line 2—2 of Fig. 1, looking at it in the direction of the arrows. Fig. 3, is a plan view on the same line, but looking in the direction of the arrows 3, 3 of Fig. 1. Fig. 4, is a plan view of a fiber disk from 75 which the cap is to be made. Fig. 5, is a side elevation of the complete cap, partly broken away to show the interior. Fig. 6, is a detail of a portion of the spring disk by which pressure is applied to the folding and 80 tucking fingers.

Same letters indicate similar parts in the different figures.

A indicates part of the frame-work of the machine upon which the moving parts 85 are mounted, and provided with the usual cushion-platform B, upon which the bottle shown in dotted lines is placed for the capping and sealing operation. This cushion platform B is intended to be thrust upward 90 by mechanism not shown, but of usual construction, as for instance the thrusting mechanism shown in U. S. Patent No. 985,141, for machinery of this class to bring the bottle which is shown in dotted lines in 95 Fig. 1, into position to be acted upon by the plunger head. C, C, represents four posts rising from the frame-work A, and supporting the guide frame D, which is yieldably sustained by the coiled springs E, E, surrounding the posts and adjustable as to their 100 degree of normal compression by the screw blocks F. The posts and the bottle are shown in Fig. 1, as broken to indicate the variable or indeterminate distance between the bottom of the guide frame and the top of the supporting cushion plate.

The guide frame D is provided with an annular opening a, of sufficient size to accommodate a variety of bottles and terminat- 110

ing at the top in a guide-ring *b*, provided with a series of recesses *c*, *c*, into which the lower ends of the fingers sink at the end of the capping movement as hereafter explained. The guide ring therefore serves not only as a guide but as a stop. Four upwardly rising pins *d*, *d*, are provided on the guide frame, which come against the lower surface of the plunger in their ascent, and lift the plunger while they permit the fingers to remain stationary until the upward movement of the bottle forces the spring-controlled fingers apart so as to close again upon the bottle neck and perform the operation of capping and sealing the bottle.

15 The plunger is mounted in a cross bar forming part of the frame work, partly shown at *A'*. The plunger consists first of a hollow stem *F'*, set in the cross-bar and provided with a set screw *f*, by which the hollow cylinder *G*, is held firmly in place in the stem. The interior of this plunger-cylinder *G*, is equipped with two spiral springs *g*, *h*, which serve to keep the plunger-rod *H*, in its outward position as shown in Fig. 1. The tension of these springs is regulated by a tension slide *i*, which may be moved more or less into the interior of the hollow stem *F'*, as required, by the screw *j*.

30 On the outer or lower end of the rod *H*, is the capping and sealing head *I*, which is removably secured thereto by a screw *k*, and is so shaped that its lower surface will press the center portion of the capping disk *K*, into the mouth of the bottle to the desired depth and size and at the same time will hold the surrounding portion of the disk firmly on the upper edge of the bottle neck. This action begins as soon as the bottle lifts the disk into contact with the lower surface of the capping head and the pressure exerted between the capping head *I*, and the bottle is constantly increased during the remainder of the lifting operation by the resilient force of the springs *g*, *h*, which are contracted in proportion to the ascent of the bottle. The shank of the capping head is slotted as at *j'* to receive a pin *k'* by which the head is prevented from turning laterally and which may also be made to serve as a stop to further upward movement.

55 Screw-threaded into the lower end of the plunger cylinder *G*, and loosely surrounding the rod *H*, is a finger-supporting flanged tube *J*, the upper surface of the flange being somewhat grooved to receive the rounded inner ends of the fingers which are rounded so as to get a proper bearing surface for the fingers when riding at different angles. As 60 usual, these fingers are arranged radially around the stem so as to form a circle and are simply hung by their inner ends upon said grooved flange. The fingers are preferably long enough to lend a certain amount 65 of flexibility to their action in distinction

from the ordinary short and rigid fingers or links frequently employed as tucking fingers. The function of these fingers is to seize the portion of the capping disk which projects beyond the periphery of the capping head *I*, 70 and bend it down and around the bottle neck rim and finally turn the extreme edge in under said rim.

The peculiarity of these fingers as I use them is that by their combination with the 75 guides, *l*, *l*, on the lower side of the plunger below the capping head, the fingers do not touch each other sidewise so as to make a practically smooth outer surface of the cap, but are held apart by the guides so as to 80 form radial ridges, *m*, *m*, as shown in Fig. 5 on the outside of the cap while the fiber of which the cap is made is forced together more closely on the inside of the cap as shown by the mere lines of division *n*, *n*, in 85 Fig. 5. These fingers *L*, *L*, are also rounded at the lower end as shown at *o*, so that they will ride over the bottle neck rim, and set the fiber disk well under the neck. They 90 also perform the functions of embossing fingers when they press the fiber down into the grooves of the guide plate and corrugate the disk before it is ironed over the bottle neck. By this combined action, the device 95 becomes a sort of combined punch and embossing die.

The various operations performed by the fingers *L*, and the various positions assumed by them, are controlled by springs which may be independent strips of spring metal 100 or may be in the form of a metallic disk *p*. They are secured by screws on the under-side of a grooved pressure plate *M*, which is keyed to the tube *J*, by a key or feather *r*. The spring action is exerted on the rounded 105 shoulders *s*, of the fingers *L*, and when a metallic disk is employed as shown in Fig. 6, it is slotted so as to give a number of peripheral tongues *t*, corresponding to that of the fingers to be acted upon. These tongues, or 110 springs, are so arranged as to over-lap an annular groove *u*, or if preferred, a succession of recesses, on the under-side of the pressure plate *M*, so as to permit the springs to bend into the recesses or groove whenever 115 the cam-like action of the rounded shoulders tends to deflect the spring. In this way the rounded shoulder serves as a fulcrum on 120 which the fingers turn as levers and the position of this fulcrum is important in order to secure a soft yielding effect on the fiber disk. As shown in Fig. 1, this fulcrum divides the fingers about as one to three, so that if the pressure exerted on the upper or short ends of the fingers is, say, ninety pounds that at the lower tips would be only thirty pounds. If however the fulcrum were placed midway of the fingers the action 125 would be too stubborn and rough and the fiber would be torn. Among the advan-

ages of this method of applying the spring pressure to the fingers L, L, may be mentioned that the fingers are thereby made independent of each other and can thus, collectively and individually, conform to the irregularities which may exist in the surface of the bottle neck to which the fiber cap is to be fitted.

The necessary pressure for operating these fingers as described, is secured as follows:— Instead of the usual single coiled spring of considerable power around the plunger stem, I employ a number of independent spiral springs of less power S, S, preferably six, which rest in sockets in the upper surface of the pressure plate M, and in the lower surface of the pressure disk N, surrounding the cylinder G, and moved up and down thereon to regulate the tension of the springs by the jam nut T, screw-threaded on the cylinder G. By dividing the spring pressure among several independent springs set radially around the plunger stem the device can accommodate itself better to uneven or irregular bottles.

The operation of my improved machine is as follows:—A bottle is placed on the cushion platform, and positioned so as to be directly under the capping head. A disk of fiber or other capping material is set on the guide ring of the guide-frame just above the bottle. By power, in the nature of a treadle or otherwise applied from below the cushion platform-frame is raised thus causing the mouth of the bottle to pass up through the guide ring, lift the capping disk, bring it into contact with the lower surface of the capping head which is pushed upward by the pins on the top of the guide frame. As the bottle is pushed farther up, into the plunger, the radial fingers are separated against the force of their spring control until the bulge of the bottle neck rim has passed their lower tips when their spring control forces the fingers inward against the outer surface of the bottle neck, thus embossing and ironing the outer portion of the capping disk around the bottle neck and tucking it in under the bottle neck rim. When the extent of the up thrust has been

reached, the return begins and during the return, the spring control of the fingers keeps up an ironing pressure on the cap as positioned on the bottle. While the spring control of the capping head retains the top of the cap in position under full pressure until the mouth of the bottle has been withdrawn from contact with the fingers when the said pressure is released, and the cushion platform descends with the bottle fully capped.

I claim:—

1. A bottle capping and sealing machine comprising a plunger composed of a spring-controlled capping head including a rod, 65 a finger supporting flanged tube loosely surrounding the rod thereof a number of radial fingers having their upper ends supported by a flanged tube, a sliding pressure plate surrounding said plunger and resting on 70 the tops of said fingers, and a number of springs arranged around said plunger and exerting pressure independently on different portions of said pressure plate.

2. A bottle capping and sealing machine 75 comprising a number of sealing fingers adapted to be arranged radially around a suitable plunger, and a corresponding number of independent springs, each acting upon the fulcrum point of a different finger, 80 whereby a lever-like action is imparted to said fingers during the sealing operation of said machine.

3. A bottle capping and sealing machine comprising a plunger, a number of sealing 85 fingers arranged radially around said plunger, a guide-ring mounted at the outer end of said plunger and having as many guide-slits as there are radial fingers and a guide-frame adapted to be moved toward said 90 plunger and having as many guide-recesses as there are radial fingers, whereby the capping material is caused to receive radial ridges during the capping and sealing operation of said machine.

JOSIAH BRADLEY.
